We claim the ornamental design for a stand for multi-function printer, as shown and described.

DESCRIPTION

FIG. 1 is a front perspective view of a stand for multi-function printer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a reduced front perspective view thereof, shown in condition of use with a multi-function printer disclosed in broken lines to illustrate an environment.

The broken lines depict portions of the stand for multi-function printer in which the design is embodied that form no part of the claimed design. Additionally, the broken lines depicting a multi-function printer in FIG. 8 are included for the purpose of illustrating environmental subject matter and form no part of the claimed design.
